UNITED STATES PATENT OFFICE

152,706

DESIGN FOR AN INTERNAL-COMBUSTION ENGINE OR SIMILAR ARTICLE

Casimir E. Leja, Chicago, Ill.

Application August 14, 1947, Serial No. 140,858

Term of patent 14 years

(Cl. D71—1)

To all whom it may concern:

Be it known that I, Casimir E. Leja, a citizen of the United States and resident of Chicago, in the county of Cook and State of Illinois, have invented a new, original, and ornamental Design for an Internal-Combustion Engine or Similar Article, of which the following is a specification, reference being had to the accompanying drawing, forming a part thereof.

As shown in the drawing, Figure 1 is a perspective view of an internal-combustion engine or similar article, showing my new design.

Figure 2 is an elevation of the same, showing the side opposite to that shown in Fig. 1.

I claim:

The ornamental design for an internal-combustion engine or similar article, substantially as shown.

CASIMIR E. LEJA.
